(boly, & yellow wood)

James MacGregor, junr. of Willow: Saratoga co. New York, a Citizen
of the United States

Improvement being a machine for
jointing, tonguing, grooving & planing
planks for flooring, houses & for
other purposes.

Date of Patent Aug 28, 1833

Do. certificate of Attorney Aug 28.

The Schedule referred to in the aforesaid Patent and making part of the
same containing a description in the words of the said James Mac
Gregor junr. himself of his Improvement, being a machine for jointing,
tonguing, grooving & planing planks for flooring, houses & for
other purposes.

Be it known that I James MacGregor junr. of Willow in the County of
Saratoga & State of New York have invented a new & useful improve
ment in the machine for jointing, tonguing, grooving & planing plank
for flooring & planks for ceiling which is described as follows:

1. The frame containing the jointing saws consists of four girths
& two cast iron side pieces, fastened together by joint bolts passing
through the sides, the top of this frame, is not quite as high as
the top of the way hereafter described.

2. The frame containing the grooving & tonguing saws
& plane, hereafter described, consists of two cast iron sides and
six girths, three of these girths are above & three below the way.

From the girths above to those below are fixed sticks on
either side of the way to which are attached cross bars fitted
for the way to rest on.

3. The way on which the timber timbers
is sixteen inches wide except between the jointing saws & between the
saws for cutting the tongue & those that cut the grooves of these

places it is only four inches. In the top of this way, the whole distance of a groove for the chain to travel in for carrying forward the plank between the saws. Forward of jointing saw the way extends further back from the jointing saw to the tonguing & grooving saw, it is off ten feet long, from this place to the wheel on which the chain goes back of the frame it is seven feet long.

This way must be even on both, so that it will not be liable to get out of place. Beyond the end of the machine the way is continued fourteen feet more.

4. The gauges on the way to guide the plank, the gauges on the way furthest from the plane shaft are made permanent & parallel with each other, the one forward of the jointing saw is a fourth of an inch farther from the center of the way than the one after the jointing saw, the jointing saw, is set to correspond with the gauge that is after it. Behind the saws that cut the tongue the gauge rests on top of the tongue to keep the plank from rising between the roller before & the one after the plane, & against the main shoulder above the tongue, to guide the plank straight, this gauge is sharp at the forward end & shaves off the caging that is above the tongue.

The gauges on the other side are movable so as to suit any width of plank. In front of the jointing saw a gauge is caught to keep the plank up to the stationary gauge.

Behind the jointing saw the gauge is as thin as possible & cast in a line with the saw. From the saws that cut the groove to the back part of the frame the shoulder of the gauge is as thick as the under flange that forms one side of the groove the edge of this flange presses against the shoulder to guide the plank straight through the machine. Above this shoulder on the gauge is a tongue that enters the groove to keep the plank from rising between the rollers.

5. The jointing done by two circular saws, the one on the surface next from the plane shaft is so placed as to cut the caged off

in a line with the grooved slot lies immediately after it, the one on the other side is placed in a moving carriage operated by a graduated, reversible, so that it can be set to any width desired.

6. The tongue of the board is formed by four circular saws, the two placed on the perpendicular shaft have a chisel between them as thick as the intended tongue, this shaft is so placed that the two saws cut horizontally into the edge of the plank as far as the width of the intended tongue. Above and below the plank is a shaft placed horizontally with one saw in each, the one above cuts down to the cut made by the upper horizontal saw, the one below cuts up to the lower cut made by the lower horizontal shaft; these two last mentioned shafts are so placed that the saws cut into the face of the plank as far from the outer edge as the tongue is designed to project.

7. The groover is formed by three circular saws placed on proper directed shafts turning horizontally in the same carriage or frame which carriage or frame is so constructed that it may be moved back or forward by a regulating screw to cut any width of plank to be desired. On one of these shafts are put two circular saws, having a chisel between them of such thickness that the saws from outside to outside will be as far apart as the width of the intended groove, the other shaft carries one saw made thicker than the two just mentioned & so placed that it cuts out the timber between the cuts made by the before mentioned saws.

8. The revolving circular planer, is made in the following manner. The shaft is of cast iron with a cast steel step fitted in its lower end & a cast steel bearing about six inches in length fitted in its upper end to admit the shaft to rise & fall without disturbing the upper box - eight cast iron arms project from this shaft at the outer sides of these is a circular cast iron rim projecting three quarters of an inch below the arms, even with the inner surface of which rim is a flange projecting horizontally one & a half inches, the under side of which flange & rim is turned true forming a smooth surface.

to pass freely over the plank to be planed. In this flange are cut out slots forming chutes to admit the varied edges of the planks, at the back part of which slots are projections extending from the top of the rim as far as the outer edge of the flange to which they are cast solid having the same inclination as the varying edge projections from the back part of the slots as well as the head pieces on which the plank was rest, & are fastened by four bolts & nuts - each plane rim is four inches long & two inches wide, rounded on the outer corner the front edge passing through the head being nearly forward, this edge the outer corner & not the outer edge as far as the plank should ever exceed the desired thickness is made sharp.

To support this revolving plane, a bar extends from one girder to another directly under the centre of the shaft below the way. On this bar is fastened a box to receive the step placed at the lower end of the revolving plane shaft. A plate forming the stationary part of this box is twelve inches long, four inches wide with a rise in the centre four inches high & four inches in diameter, this the centre of which is drilled an aperture two inches in diameter in a line with the centre of the shaft in this aperture is fitted a piece of metal having a cavity in its upper end to admit the point of the shaft. It is made to rise & fall by a regulating screw to elevate the surface the plane at pleasure; the side of the rise is tappet & a screw fitted in to it, press against the side of the slide to keep it stationary when required.

4. The feeding is performed by an endless chain passing over two wheels one at the end of the frame in which the revolving plane is placed & the other at the first end of the way, the first mentioned wheel has cogs on its periphery working in the links of the chain - on this chain are fastened hooks which lay hold of the end of the plank on the chain carrying it forward to the end of plane. 10. Rollers for holding down the plank, there are three of these

rollers, one placed in front of the jointing and tongueing saws, and between these & the planer, & the other behind the planer all held down upon the plank by weights & levers to confine the plank on the way.

11. The pulley & bands on each of the shafts of the saws & on the shaft of the revolving planer is fixed a pulley.

Another pulley is put on the feed shaft by going across the frame below the ways. A pulley is fixed on a shaft at the after end of the frame on this shaft is a small cog wheel working into a large cog wheel on the shaft of the wheel carrying the endless chain. A large pulley or drum & a broad pulley are placed under the way & at right angles with it between the two frames. A band passes around each pulley & around the large drum for driving the jointing saws, tongueing & grooving saws and the revolving planer.

The band which drives the feeding pulley passes around a small pulley on the shaft of the main drum. The driving pulley is also placed on the shaft.

Operations. The machine being put in motion by steam or water power, the plank to be dressed is placed on the way in front of the jointing saws & carried forward by the motion of the endless chain to these saws which joint its edges, it is then carried forward to the tongueing & grooving saws passing over the rollers between the guides where it is tongued and grooved in the manner heretofore described, the endless chain then carries it forward to the circular revolving planer when it is planed smooth by the operation of the planer in the same way as herein before described.

The plank is then conducted out of the machine by the continued motion of the endless chain. The jointing may be performed in a separate machine & the tongueing & grooving - and the planing operation may be done in a machine distinct from the others but all operated on the same principles as herein described. Rather

may also be sawn before & and after the joining, so to keep the plank firmly drawn upon the way.

This is what I the said James MacGregor first claim as my invention & for which I do此刻 obtain Patent from the Government of the United States in. 1. The planing of timber of any size, or dimension, by the principle of the turning tools & plane now used as before described, or by the turning tools separate from the plane, so as to retain the same principle. 2. The application of the sliding box for the stop of the revolving plane shaft to turn in & by which the revolving plane is raised & lowered, to give the desired thickness to the planks made & applied as before described.

3. The passing the shaft this beyond the face of the revolving circular plane so as to have a step for the plane to rest on. 4. The application of the gauge under the plane to keep the stuff down while the plane is operating, this may be done by a roller, but I prefer the gauge. 5. The application of the common circular saw to joint tongue & groove plank or siding, in the manner before described. 6. The mode of forming a tongue on a board plank or siding by cutting in the edge of the plank horizontally on each side of the tongue & then vertically to form the shoulder by circular saws as herein before described. 7. The mode of forming the groove by making two horizontal cuts in the edge of the plank with two circular saws as far apart & as deep as the width & depth of the intended groove & clearing out the timber between these cuts by a circular saw revolving horizontally in the manner herein described.

Further to illustrate my invention I refer to the model & Drawing of the same deposited in the Patent Office.

In Testimony whereof I hereunto subscribe my name this

19th day of August 1833

Witnesses.

James MacGregor Invent.
